PAPER FEEDING DEVICE

Fred M. Roque, New York, N. Y.

Application February 8, 1936, Serial No. 62,895

2 Claims. (Cl. 271—42)

The present invention relates to paper feeding devices, and more particularly adapted to feed single sheets from off a pile, in succession and in proper frequency, into duplicating machines, as for instance, what commonly are known as mimeograph machines and the like.

The principal object of this invention is to provide a device of the character described, which is of novel, improved and extremely simple construction, embodying less parts and employing less moving parts than occur in devices of similar purpose heretofore known.

Another object of the present invention is to provide a paper feeding device of the class mentioned, which is cheap to manufacture, certain in action and efficient in use.

To attain these objects, and others which will become manifest as this disclosure proceeds, in an embodiment of my present invention as adapted for use for instance with a mimeograph machine, I provide a table, whereon shall rest the pile of sheets to be singly fed, over which is a horizontally journaled shaft which carries a sheet-shifter arm for periodic contact with the top sheet of paper, and a cam-follower arm for rolling contact on, and to and fro along a cam which is carried on a connecting rod adapted to oscillate said shaft towards and away from the drum of the aforesaid machine; the contour of the surface of the cam being such, that on the forward movement of said shaft, the sheet-shifter arm is in contact with the top of the pile, while on the backward movement of the shaft, said arm is off the pile.

This invention is capable of numerous forms and various applications without departing from the essential features herein disclosed. It is therefore intended and desired that the embodiment shown herein be deemed illustrative and not restrictive, and that the patent shall cover whatever features of patentable novelty exist in the invention disclosed; reference being had to the appended claims rather than to the specific description herein to indicate the scope of the invention.

In the accompanying drawings, forming part of this application, similar characters of reference indicate corresponding parts in all the views.

Fig. 1 shows in perspective, an embodiment of the present invention used in connection with a mimeograph machine.

Fig. 2 is a front view of Fig. 1, showing the relative position of the various essential components at the commencement of the sheet feeding stroke.

Fig. 3 is a similar view at the end of the feeding stroke, which is the commencement of the return stroke.

Fig. 4 is a top view of my device shown in Fig. 3.

In the drawings, the numeral 10 is used to indicate generally a mimeograph machine or device of similar purpose, having a drum 11 and a shaft 12, which latter rotates once per revolution of said drum. I provide a table 13, having 10 its side legs 14, secured to the frame of machine 10. A pile of paper sheets 15, rests on said table between the pairs of guides 16 and 17, which can be slid along the slots 18, and fixed at any position by means of the nuts 19. The guides 15 16 have a facing of sponge rubber 20.

A yoke, indicated generally by the numeral 21, comprises the substantially upright parallel arms 22, one at each side of the table 13, carried on a shaft 23 which is mounted horizontally through the table legs 14. 24 is a tie rod between said arms 22. A shaft 25 is horizontally suspended between the top ends of the arms of said yoke 21, and is removably journaled therein. This shaft is parallel to the axis of the drum 11.

At about the middle, there extends from shaft 25, a sheet-shifter arm 26, which terminates at its free end in a sponge rubber shoe 27, for contact with the top of pile 15, and at an end, there extends from said shaft, a cam-follower arm 28, having a roller 29 at its free end, for rolling contact on, and to and fro along a cam member 30, which is integral with, or as shown secured to a connecting rod 31, to be carried thereby. This connecting rod is pivotally linked at its ends to an arm of the yoke 21, at point 32, and to a crank member 33, which latter is carried on a projecting end of shaft 12. The contour of the contact surface of the cam 30, is essentially 40 intermediate an incline 35 upwards towards the drum 11, and the incline 36 downwards away from said drum.

In operation, referring to Fig. 2, which illustrates the condition at the commencement of the sheet feeding stroke, the shoe 27 of the shifter arm 26, is in frictional contact with the sheet of paper uppermost on the pile 15, and as shaft 12 rotates, the action of the connecting rod 31, 50 will bring the yoke 21 and all it carries, towards the drum 11, and said top sheet of paper will be shifted or slid partially off the pile and fed into the machine 10. Said shoe 27, will remain in constant contact with the top sheet during the 55

entire feeding stroke, for at no time during such forward movement will the cam 30 cause arm 28 to be lifted. However, as soon as this forward stroke is completed, the moving connecting rod 5 31 will carry cam 30 upward to make contact with and suddenly lift the roller 29, whereby shaft 25 will rotate slightly clockwise, thus lifting shoe 27 upward and off the pile 15.

I now refer to Fig. 3, which illustrates the condition at the commencement of the backward stroke where shoe 27 has just been lifted off the pile 15. As shaft 12 continues to rotate, the roller 29 will move backward along the contour surface of the cam 30, for geometrically speaking, there occurs a change of shape of the triangle formed by the lines of the connecting rod 31, the cam-follower arm 28, and the yoke arm 22, and at the end of the stroke, said roller will finally fall down the incline portion 36, causing shoe 27 to resume contact with the pile 15, ready to repeat the cycle with respect to the sheet of paper now on top of the pile. It is to be noted that the shoe 27 for the greater part of the backward stroke, rides along a practically horizontal line.

25 Adjustment of the position of pivot 38 along slot 37 in the crank member 33, accomplishes a change of the line of shoe and sheet contact, towards or away from the drum 11, for it is desirable to use this feeding device for various 30 sizes of paper.

I claim:

1. In a paper feeding device of the class described, a table, an arm pivoted at the side of the table and extending above the plane thereof, a crank, a connecting rod pivotedly linked to the 5 crank and arm to oscillate the latter, a cam member carried on the connecting rod, a shaft journalled in the arm and extending over and above the table, a sheet shifter arm and a cam follower arm, both carried on and extending from the 10 shaft and means to rotate the crank; the cam follower arm being in such position on the shaft for contact with, and periodic movement to and fro along the cam member.

2. In a paper feeding device of the class described, a table, a yoke including a pair of parallel arms pivoted at opposite sides of the table and each of said arms extending above the plane of the table, a crank, a connecting rod pivotedly linked to the crank and one of said yoke arms to 20 oscillate said yoke, a cam member carried on the connecting rod, a shaft journalled in said arms and extending over and above the table, a sheet shifter arm and a cam follower arm, both carried on and extending from the shaft and means to 25 rotate the crank; the cam follower arm being in such position on the shaft for contact with, and periodic movement to and fro along the cam member.

FRED M. ROQUE. 30
